United States Patent Office

Des. 211,001
Patented May 14, 1968

211,001

JUG

Franklin Douglas Northgrave, London, Ontario, Canada,
assignor to London Winery Limited, London, Ontario,
Canada

Filed Jan. 11, 1967, Ser. No. 5,379

Term of patent 14 years

Claims priority, application Canada Oct. 27, 1966

(Cl. D9—49)

FIG. 1 is an elevational view of a jug embodying my new design;

FIG. 2 is an elevational view looking from the right of FIG. 1; and

FIG. 3 is a top plan view thereof.

I claim:

The ornamental design for a jug, as shown.
